ELECTRIC SOCKET SWITCH

Filed Sept. 20, 1921

INVENTOR

UNITED STATES PATENT OFFICE.

WILLIAM F. CONKLIN, OF TARENTUM, PENNSYLVANIA.

ELECTRIC SOCKET SWITCH.

Application filed September 20, 1921. Serial No. 502,021.

My invention consists of an improvement in detachable electric socket switches, and has for its object to provide a socket and stem combination switch, by which the stem or shank of the circuit opening and closing member may be easily inserted or removed or fixedly held within the receiving socket.

It comprises a special socket construction embodying an insertion or clearance opening 10 for the locking and circuit closing lugs of a conducting key bolt or stem, registering sockets therefor embodying circuit terminals, and a spring operable to seat the contacting lugs in such sockets for fixed engagement, capable of compression to admit of unseating and turning of the bolt or stem and its contact lugs for clearance through the insertion opening, for insertion or removal.

20 The objects in view are to provide a simple and efficient means for inserting, locking, and removing the inner end of a combined contacting and locking stem or shank, capable of holding the stem in securing position for establishing circuit therethrough to an outer terminal for any current utilizing device, as a lamp or the like, and constructed and adapted to operate in the manner more fully hereinafter set forth.

30 In the drawings, illustrating one preferred embodiment of the invention,

Fig. 1 is a longitudinal central section through an electric socket switch, showing the same in operative position;

35 Fig. 2 is a detached view in elevation of the central removable stem or plug;

Figs. 3, 4, 5 and 6 are sectional views on the lines III—III, IV—IV, V—V, and VI—VI respectively of Fig. 1;

40 Fig. 7 is a detached perspective detail view of one of the lug-engaging and locking contacting terminals;

Fig. 8 is a detail view in elevation of one of the conducting sides of the removable stem;

Fig. 9 is an end view thereof;

Fig. 10 is a perspective detail view of the insulating bushing for the socket;

Fig. 11 is a detail view showing the 50 mounting of one of the contact terminals in the insulating block providing the lug engaging socket; and

Fig. 12 is a sectional detail view showing a modified construction of stem adapted for 55 the opening and closing of a circuit through the socket in the manner of a switch.

The device as a whole is designed to be mounted upon a wall or incorporated therewith, or in any other suitable location and in electrical connection with a source of current, so that it may be utilized at any of several predetermined locations, for the purpose of connecting and disconnecting, by the insertible stem or plug, with a lamp, electric heater, cooker, iron, or any of the various current utilizing elements in common use, whereby to enable the user to make easy and convenient current connection at or adjacent to the point of use of the current.

To this end, I provide a socket member A and a removable plug or stem member B, the latter being capable of insertion centrally of the former and therein held in locked position during the period of current consumption. Socket member A is composed of an outer housing or casing 2 having terminal flanges 3, whereby the socket may be fixedly secured in position by screws or otherwise, as upon the studding or supporting framework of a wall or the like. It is of generally cylindrical form and may be embedded in a wall with its outer end portion flush therewith so as to occupy a minimum of space and remain inconspicuous or in any way interfere with the wall surface.

Within the casing 2 are mounted insulating block members 4 and 5 respectively which are held in position by longitudinally extending bolts or screws 6—6 tapped into a rear terminal washer bearing 7, of steel or other suitable material. Washer 7 is in flanged engagement with the inner portion of insulating block 4 and preferably flush therewith at its inner end, providing a flush attaching surface for the socket member and fixedly holding the several parts in operative position. Outer insulating block 5 is provided with a central oblong opening 8 within which extends the shell 9 forming an interfitting insulating bushing having a lateral flange 10 extending between the insulating blocks 4 and 5.

Fixedly secured in receiving sockets of block 5 and held in place by the flange 10, are the two oppositely located contact blocks 11 each preferably provided with a sloping contact face 12 for engagement with the contact lug 13 of the central stem of the removable plug member B. Insulating block 5 has an oppositely sloping face 32 providing between it and the tapered face 12 of contact block 11 an inwardly tapering

socket adapted to receive the double contact lugs 13 to ensure continued contact under the spring pressure hereinafter described. Blocks 11 are in electrical connection by screws 14 and wires 15, one at each side, with a generator or other source of current.

The plug member B, as shown in the principal views of the drawings, is a compound member formed of individual conducting strips 16 each provided with the extended contact lug member 13 and having an outer terminal enlargement 17 for fixed connection with the attaching terminal shell member 18. The latter member is preferably circular in form, embracing the semi-circular terminals 17 of the compound conducting stem members, with an intervening insulating cap or shell 19. Terminal member 18 is connected with the terminal 17 by screws 20 extending through its shell and insulation 19 and an additional insulating disk 21 on the inner face thereof, being held in position by nuts 22, as shown.

Lead wires 23-23 are connected at each side with the individual conducting members 16 of the compound plug by binding screws 24 and the shell 18 is provided with an extended threaded terminal 25 for connection with a lamp socket, chandelier, or any other utilizing element, as will be readily understood.

Conducting members 16 of the compound plug are insulated from each other by an intervening strip 26 of fibre or the like, and the outer surfaces of the plug are further insulated by fibre or other casings 27 and 28, which completely embrace them at all points except where the contact lug members 13 extend, which alone are exposed.

The inner portion of the socket member A is provided with a dielectric bushing 29 providing a lining for the inner central portion of washer 7 and secured thereto in any suitable way, which bushing forms a central cylindrical bearing for the inner end of the compound plug member. Between bushing 29 and a resisting washer 30 is interposed a compressible spiral spring 31, adapted to press the compound plug member outwardly after insertion through slot 8 and beyond the flange 10, the plug then being partially rotated, so as to bring the contact lugs 13 at each diagonally opposite side into interfitting register and electrical engagement with the co-acting terminal contact members 11 and faces 12 thereof, and the opposing tapered faces 32 of insulating block 5.

The relative positions of the contact members 13 and blocks 11 are clearly shown in Figs. 4 and 11, closing the circuit. To open the circuit, the compound plug member is thrust inwardly against spring pressure sufficiently far to bring the contact lugs 13 inwardly beyond the inner edge portion of

flange 10, away from faces 12, so that the plug may be reversely rotated one-quarter way around, at the same time pressing spring 31, by engagement of the lugs against washer 30, so that the plug may then be withdrawn, the lugs 13 passing outwardly through slotted opening 8.

Upon inserting the plug, partially rotating it, and then relieving pressure, the spring will re-act and thrust the stem outwardly, bringing the tapering faces of lugs 13 into binding engagement with faces 12, and also with diagonally opposite tapering faces 32 of the insulating block 5. By this means, the spring action ensures tight engagement between the conducting elements and fixedly holds the plug in closed circuit position, until it is desired to remove it, as described. The spring 31 will act to seat washer 30 against the inner end of flange 10, when the socket is inactive, ready for reinsertion of the plug when again used, in the same manner as above described.

If desired, the central plug may be utilized to merely close the circuit across the socket A by making it of a single central conducting stem 16^a, with laterally extending lugs 13^a, as shown in Fig. 12, in which case the plug will operate to close the circuit across the terminal members 12 instead of providing for carrying it outwardly through the individual insulated conducting members 16 of the compound plug.

The construction and operation of the invention will be readily understood and appreciated from the foregoing description. It provides easy and convenient means for installing and readily removing electric lamps or other forms of electric fixtures or current consuming devices, without disturbing the wiring and without the use of tools. Any electrical fixture or device may thus be moved from one socket to another without leaving any exposed wiring; fixtures may be taken down from the side walls or ceilings of buildings, or for the purpose of cleaning, papering, or painting, and then immediately replaced without disturbing any of the connections.

The invention may be variously changed or modified in different details by the skilled mechanic to adapt it to various local or other conditions of use, but all such changes are to be understood as included within the scope of the following claims.

What I claim is:

1. In an electric socket switch, an insulating body portion having an outer casing and an inner block provided with a slotted opening extending endwise therethrough and having at its inner end laterally arranged sockets, contact members forming portions of said sockets and having current supply connections, an insulating shell with- 125
130

space opening through the end of the casing and having an inner flange, a depressible washer plate adapted to bear against the flange, a spring bearing by one end 5 against said washer plate and by its other end against an abutment within the casing, a rotatable insertible plug having lateral contacting extensions adapted to engage the washer plate, substantially as shown and 10 described.

2. A separable connector for electric conductors comprising a socket member and a plug member, said socket member comprising a casing, an insulating sleeve in the casing which is substantially rectangular in cross section and is flanged at its inner end, both ends of the sleeve, through which is 15 a substantially rectangular opening, being open, the front of the sleeve terminating 20 substantially flush with the front of the casing, the flange being disposed intermediate

the ends of the casing, insulating bushings in the casing for holding the sleeve in place, a circular chamber at the rear of the flange, said sleeve having openings cut in the flange 25 and longer sides of the sleeve, contact members in juxtaposition to the openings and outside the sleeve, the plug having a central pin with transverse contacting extensions 30 slidible in the sleeve when turned to the proper position, said chamber at the rear of the plunger enabling the plug to be turned when inserted in the sleeve to its fullest extent so as to enter said openings and engage the contact members, and means 35 for yieldably urging the plug member outwardly and thereby hold the contacting extensions in sleeve engagement with the contact members.

In testimony whereof I hereunto affix my 40 signature.

WILLIAM F. CONKLIN.
